Primary Examiner — Melanie H Tung*Assistant Examiner* — Lavone D Tabor(74) *Attorney, Agent, or Firm* — Carter, DeLuca, Farrell & Schmidt, LLP(57) **CLAIM**

The ornamental design for the hair brush, as shown and described.

DESCRIPTION

FIG. 1 is a perspective view of the hair brush in accordance with the principles of the present disclosure;

FIG. 2 is a rear axial view of the hair brush;

FIG. 3 is a first side elevation view of the hair brush;

FIG. 4 is a front axial view of the hair brush; and,

FIG. 5 is a second side elevation view of the hair brush.

The series of outer broken lines shown on the head and the broken line immediately adjacent the shaded area near the distal end of the handle represent the bounds of the claim and form no part thereof while all of the other broken lines showing parts of the head, the bristles, the structure within the head, and parts of the handle illustrate portions of the hair brush that form no part of the claimed design.
